FIG. 1

FIG. 2

FIG. 3

FIG. 5

CHARLES C. SPREEN
INVENTOR

BY *Smith and Freeme*
ATTORNEYS

UNITED STATES PATENT OFFICE.

CHARLES C. SPREEN, OF DETROIT, MICHIGAN.

REFRIGERATION.

Application filed February 21, 1927. Serial No. 169,758.

My invention relates to refrigeration, and particularly to means for increasing the absorbing power of the heat absorbing unit, and the particular object of my invention is to 5 provide new and improved means of this type. In the drawings accompanying this specification and forming a part of this application I have shown, for purposes of illustration, three forms which my invention may assume, 10 and in these drawings:

Figure 1 is a side elevation of one embodiment of my invention, while

Figures 2, 3, 4, and 5 are details of other embodiments of my invention.

15 The embodiment of my invention shown in Figure 1 comprises a plurality of plates 11 having apertures 12 of a size to fit closely over the body of an expander drum 13, of the usual float valve type, disposed at spaced intervals throughout the longitudinal extent 20 of the expander drum 13. The apertures 12 of the plate 11 are surrounded by flanges 14 for positioning the plates in planes at right angles to the longitudinal axis of the expander 13 and the plates serve to greatly increase the heat absorbing power of the expander 13.

In the embodiment of my invention shown in Figures 2 and 3 the plates 15 have apertures 16 disposed laterally of the apertures 17 30 engaging the expander 18 which receive sleeve-like ice tray supports 19.

In Figure 4 the ice tray receiving means are formed by flanges 20 surrounding the 35 apertures 21 and of such width that when the plates 22 are assembled on the drum 13 the flanges of each plate engage the surface of the adjacent plate whereby the several flanges form a tube-like recess having continuous

walls and passing through all of the plates 22. 40

The plates in any of these embodiments may be corrugated as shown in Figure 5.

From the above disclosure it will be obvious to those skilled in the art that I have provided new and improved means for increasing 45 the absorbing power of a heat absorbing unit in a mechanical refrigeration system.

At the same time it will be obvious to those skilled in the art that the embodiment of the invention herein shown and described may be 50 variously changed and modified without departing from the spirit of my invention or sacrificing the advantages thereof, and it therefore will be understood that the disclosure herein is illustrative only, and that 55 my invention is not limited thereto.

I claim:

1. In a mechanical refrigerating system, a cooling unit including a liquid refrigerant container, a plurality of fins formed of sheet 60 metal, said fins having apertures through which said container extends, and flanges on said fins removed from said container, said flanges surrounding apertures in said fins and forming therewith a tray support. 65

2. In a mechanical refrigerating system, a cooling unit including a plurality of fins having spaced openings formed in two aligned rows, flanges surrounding one row of apertures and extending from each fin to the adjacent fin, and a container extending through the other row of apertures in said fins, said container supporting said fins and arranged in thermal contact therewith. 70

In testimony whereof I hereunto affix my 75 signature.

CHARLES C. SPREEN.
